H. C. REUTER,

GUN CASE,

APPLICATION FILED FEB. 10, 1916.

1,187,652.

Patented June 20, 1916.

UNITED STATES PATENT OFFICE.

HERMAN C. REUTER, OF NEW BERLIN, OHIO, ASSIGNEE TO THE W. H. HOOVER COMPANY, OF NEW BERLIN, OHIO, A CORPORATION OF OHIO.

GUN-CASE.

1,187,652.

Specification of Letters Patent. Patented June 20, 1916.

Application filed February 10, 1916. Serial No. 77,408.

To all whom it may concern:

Be it known that I, HERMAN C. REUTER, a citizen of the United States, residing at New Berlin, in the county of Stark and State of Ohio, have invented a new and useful Gun-Case, of which the following is a specification.

My invention relates to improvements in gun cases in which an adjustable partition 10 is located whereby the case proper is divided into two compartments.

The objects of the present invention are, first, to so attach the partition to the case that the same cannot become twisted or 15 turned, second, to so attach the partition that its position may be changed to accommodate different sized stocks and barrels, third, to so attach the partition that regardless of the manner in which the case is carried there can be no direct contact as between the gun barrel and stock. These objects, together with other objects readily apparent to those skilled in the art, may be attained by the construction illustrated in 20 the accompanying drawings, although the invention may be embodied in other forms, the construction illustrated being chosen by way of example.

In the accompanying drawing: Figure 1 30 is a longitudinal section showing the gun barrel and stock placed within the case. Fig. 2 is a longitudinal section of the case, showing by dotted lines the extreme movements of the partition. Fig. 3 is a trans- 35 verse section on line 3—3, Fig. 2.

Similar numerals of reference indicate corresponding parts throughout the several figures of the drawing.

In the accompanying drawings, 1 represents the case, which is of the usual construction and within itself forms no specific part of the present invention, except that a case similar to the one shown must be employed, the specific construction of the 40 case as well as the closure 2 being immaterial. To the side members of the case 1 are attached, preferably by stitching, the fibrous strips 3, which strips are also connected by some adhesive substance to the partition 45 plate 4, but the particular manner of attaching the strips 3 to the partition 4 is immaterial, the only object being to so attach the strips to the partition plate that they will not become detached from use. In gun 50

cases of the character described, it is of importance that the partition which divides the case into the stock compartment and the barrel compartment be so connected that it cannot tilt or twist and allow the direct contact of the barrel with the stock or vice versa. It will be understood that by connecting the pliable strips 3 to the sides of the casing, and also to the partition plate that no twisting or tilting of the plate can take place, thereby preventing any accidental contact of the gun parts, regardless of the position or rough handling of the gun case. It will be understood that the strips 3 should be formed of sufficient width to allow the proper degree of adjustment, which adjustment in ordinary cases does not exceed more than two inches, but of course, this adjustment may be varied by increasing or decreasing the width of the strips 3. By forming the strips of the desired width and 70 of a length to correspond with the length of the partition plate, said partition plate can be brought into the positions illustrated in dotted lines Fig. 2, owing to the fact that both ends of the partition plate are free to 75 move up and down, and the partition plate located at any angle with reference to the case within the limits of the movements of the partition plate. It will also be understood that the partition plate can be adjusted in different parallel planes, owing to 80 the fact that neither end of the partition plate is immovably connected to the case.

Having fully described my invention, what I claim as new and desire to secure by 90 Letters Patent, is:

1. In a gun case of the character described, the combination of a case, pliable strips secured to the side walls of the case, and a partition plate secured to said strips. 95

2. In a gun case of the character described, the combination of a case, a partition plate adapted to divide the case into compartments, and pliable strips located upon opposite sides of the partition plate, 100 said strips secured to the side walls of the case, and the strips formed of a length to correspond with the length of the partition plate.

In testimony that I claim the above, I 105 have hereunto subscribed my name.

HERMAN C. REUTER.
